UNITED STATES PATENT OFFICE.

SAMUEL M. CURWEN, OF HAVERFORD, AND WARREN M. SMITH, OF MOORES, PENNSYLVANIA,
ASSIGNORS TO THE J. G. BRILL COMPANY, OF PHILADELPHIA, PENNSYLVANIA, A COR-
PORATION OF PENNSYLVANIA:

PASSENGER-CAR.

No. 902,381.

Specification of Letters Patent.

Patented Oct. 27, 1908.

Application filed May 4, 1908. Serial No. 430,820.

To all whom it may concern:

Be it known that we, SAMUEL M. CURWEN and WARREN M. SMITH, citizens of the United States, residing in Haverford, and 5 Moores, Pennsylvania, respectively, have invented certain Improvements in Passenger Cars, of which the following is a specification.

Our invention relates to certain improvements in cars of the type in which a passenger pays his fare before entering the car.

One object of our invention is to so construct the car that the dividing partition or rail separating the platform into ingress or 15 egress sections will extend into the body of the car past the doorway and yet will allow for the closing of the doors.

Our invention further relates to certain improvements in seat structures for the platform, applied to this type of car.

A further object of the invention is to convert the ordinary type of car into one in which the fare is paid on entering the car.

In the accompanying drawings:—Figure 1, 25 is a sectional plan view of one end of a passenger car illustrating our invention; Fig. 2, is a longitudinal section on the line 2—2, Fig. 1; Fig. 3, is a sectional plan view similar to Fig. 1, showing the doors closed and the seats extended; Fig. 4, is a sectional view on the line 4—4, Fig. 1, showing the seats folded; Fig. 5, 30 is a sectional plan view on the line 5—5, Fig. 4, showing the seats extended; and Fig. 6, is a view looking in the direction of the 35 row 6, Fig. 4.

D is the body of the car.

E is the platform.

D' is a transverse partition separating the platform from the body of the car, and in 40 this partition is the ordinary doorway d closed by sliding doors d' of the usual type.

E' is the ordinary end vestibule section of a platform.

E² is a fixed side having a channel f for a 45 sliding door F, which is the exit door when the platform is at the forward end of the car. On the opposite side is a series of doors G, which, in the present instance, can be folded back against the section E' of the vestibule, 50 if desired, or other types of doors may be used without departing from our invention.

A is the rail separating the platform E into ingress and egress sections e and e', and this rail is offset at a to allow additional room for 55 the conductor to stand on the egress section of the platform. The rail terminates at the

doors d' and an extension A' of this rail is secured to the floor of the body D of the car and extends into the car so as to divide the doorway and the body of the car near the 60 doorway into egress and ingress passageways i and i', so as to prevent the passengers crowding in passing through the doorway.

The rail A is made with a section a' below the main rail which not only acts as a guard 65 but also carries the pivoted seat sections B, B', as shown in Fig. 4. Each section is made in two parts b, b' hinged together as shown and, in the present instance, they have hooked ends b² which engage the sockets c, c' 70 on the framework of the car when the seats are extended for use. Folding brackets g on the doors support the said sections at the center when extended; and when the sections are folded out of the way, as illustrated in Fig. 75 4, they do not interfere with the ingress and egress of passengers. When the platform is at the forward end of the car and the doors G closed then the seat sections may be extended for the use of passengers. 80

We claim:—

1. The combination in a passenger car, of a body portion, a platform, a transverse partition separating the platform from the body of the car, a doorway therein, doors adapted 85 to close the doorway, a rail dividing the platform into ingress and egress sections, and a continuation of said rail extending into the body of the car beyond the doors.

2. The combination in a passenger car, of a body portion, a platform, a partition separating the platform from the body of the car and having a doorway therein, sliding doors for closing said doorway, and two rails dividing the doorway into ingress and egress 95 sections, one rail being within the car and terminating at the door, the other rail being on the platform and terminating at the door.

3. The combination in a passenger car, of a body portion, a platform, a partition separating the platform from the body of the car and having a doorway therein, sliding doors for closing said doorway, and two rails dividing the doorway into ingress and egress sections, one rail being within the car and terminating 100 at the door, the other rail being on the platform and extending at an angle from the door towards the side of the platform.

4. The combination in a passenger car, of a body portion, a platform, a transverse partition dividing the platform from the body of the car and having a doorway therein, slid- 110

ing doors for closing said doorway, two rails, one on the inside of the car and the other on the platform and dividing the doorway into two passageways, the platform rail continuing at right angles towards one side of the platform and offset to increase the size of the egress section of the platform for the purpose described.

5. The combination in a passenger car, of a platform, a rail separating the platform into ingress and egress sections, a folding seat hung on said rail, and means for supporting the seat section in its extended position.

6. The combination in a passenger car, of

a platform, a rail dividing the platform into 15 two sections, folding seat sections, one suspended from each side of the rail, and means for supporting each section in its extended position.

In testimony whereof, we have signed our 20 names to this specification, in the presence of two subscribing witnesses.

SAMUEL M. CURWEN.
WARREN M. SMITH.
